UNITED STATES PATENT OFFICE.

HENRY BAUER, OF BUFFALO, NEW YORK.

WEATHER-STRIP FOR DOORS.

1,145,539.

Specification of Letters Patent. Patented July 6, 1915.

Application filed June 23, 1913. Serial No. 775,406.

To all whom it may concern:

Be it known that I, HENRY BAUER, a citizen of the United States, residing at Buffalo, in the county of Erie and State of New York, have invented certain new and useful Improvements in Weather-Strips for Doors, of which the following is a specification.

My invention relates to weather strips for doors, and more particularly to that type in which the strip proper moves automatically in contact with the floor upon closing the door to which it is applied.

The invention has for its object the provision of a weather strip of the type mentioned which is simple in construction, inexpensive and durable and in which projecting parts are dispensed with so that there is no liability of clothing being caught in passing through the door opening.

To this end the invention consists in the novel features of construction and in the combination and arrangement of parts to be hereinafter described and more particularly pointed out in the appended claims.

In the drawing in which like numerals of reference refer to like parts, Figure 1 is an elevation of the lower portion of a door and the wall adjoining, the lower end of the door and a part of the door casing being broken away to illustrate the invention; the door being shown closed with the weather strip proper in contact with the floor. Fig. 2 is a similar view of the door showing the position of the parts when the door is ajar. Fig. 3 is an enlarged vertical section taken on line 3-3, Fig. 1. Fig. 4 is a detached perspective view of one of the metallic guide members secured in the lower end of the door. Fig. 5 is a perspective view of a portion of the weather strip proper. Fig. 6 is a detached perspective view of the actuator.

The reference numeral 7 designates a wall, 8 the door and 9 the door-jamb to which the door is hinged.

The door is provided with a longitudinal groove or recess 10 at its lower edge which has that end adjacent the unhinged vertical edge of the door closed, as at 11, the wall of the groove or recess at said end being inclined so that sufficient material of the door remains to assure durability and strength at such point. The opposite end of said groove or recess is increased in depth, as at 12, to allow freedom in action of an actuator 13.

14 designates two guide members which are fitted into the groove or recess 10 at points between its ends, said guide members being spaced apart and each being of channel shape to provide an inner wall 15 which bears against the inner wall of said groove or recess and side walls 16 which lie against the side walls of said groove or recess. Each of these guide members has also opposite lateral webs or extensions 17 which bear against the lower edge of the door, being preferably recessed therein and secured by screws. These guide members, by reason of their construction and manner of securing them to the door can be made of light sheet metal, and the side walls 16 of each are provided with aligned obliquely-disposed guide slots 18 formed by slitting the metal and bending webs 19 outwardly therefrom, which webs are ranged along the upper edges of the slots and serve as bearing pieces which provide extended contact faces.

The weather strip proper is designated by 20 the reference numeral 20 and consists of a longitudinal wooden or other suitable body-portion 21 of a size in cross section to freely fit into and move within the groove or recess 10 and within the guide members 14 and of a length to extend almost from one vertical edge of the door to the other. This strip is grooved along its lower edge to receive a yielding contact element 22 of felt or any other suitable material, said contact element 23 projecting beyond the lower edge of said strip and adapted to be brought into contact with the floor when the door is closed so as to close the space between the two, as clearly shown in Fig. 1.

The end of the weather strip proper adjacent the unhinged vertical edge of the door is inclined, as at 23, to correspond to the inclined wall of the groove or recess 10 at that point and preferably bears against said inclined wall, and attention is directed to the fact that the inclination of the wall of said groove or recess and that of said strip is at the same angle as the guide slots 18.

Passing through the weather strip are pins 24 which project from opposite sides thereof and enter the guide slots 18 in the guide-members 14, said pins being adapted to move in contact with the webs 19 of said members. By exerting pressure lengthwise on the weather strip in the direction of the

arrow 25 in Fig. 2, it is moved toward the unhinged vertical edge of the door and also toward the floor, a lengthwise movement with a component downward movement is therefore obtained, due to the strip being guided by its inclined end and the pins 24.

The power to actuate the weather strip proper is obtained through the actuator 13 which is slidable in the enlarged portion 12 of the groove or recess 10, said actuator comprising a yoke or frame 26 having a longitudinal member 27, parallel arms 28 depending from opposite ends of member 27 and an actuator member 29 inclined in opposite direction to the slots in the guide members 14, said actuator member entering a similarly inclined slot 30 in the weather strip 20. To increase the durability of the device I preferably provide a metallic member 31 in which the slot 30 referred to is formed, said member being recessed into the body portion of the weather strip and secured thereto by screws or otherwise.

Extending through the arms 28 of the actuator yoke or frame is a rod 32, said rod being threadingly engaged with said arms so that it may be adjusted therein, for a purpose to presently appear. This rod extends forwardly and rearwardly from said actuator yoke or frame, as at 33, 34, the forward end being guided in a bore 35 in the door and the rear end being guided in a metal guide plate 36 secured to the hinged edge of the door and closing the inner end of the groove or recess 10.

Secured to the door jamb 9 is a metal wear plate 37, which is desirable in use but not necessary and the rear end of the actuator rod 32 is adapted to bear against said wear plate, or in the absence of the latter, against the jamb proper, which the wear plate may be considered part of when used.

Interposed between the shoulder 38, formed by the increased depth of the groove or recess 10, and the forward arm 33 of the actuator yoke or frame is a spiral spring 39 which surrounds the forward portion of the actuator rod 32 and serves to force and hold said rod and the yoke or frame carried thereby in its rearmost position with the rear end projecting or tending to project beyond the outer face of the guide plate 36, depending on whether the door is open or closed. By reason of the connection of the actuator with the weather strip the latter is drawn rearward with the actuator and moves upward when the actuator is in its rearward position, which position it is allowed to assume when the rear projecting end of the actuator rod 32 finds no obstruction to its movement, such as the door jamb, and since in opening the door the hinged edge thereof moves away from the jamb and out of opposition thereto, said rod is forced outward by the spring 39. When, however,

the door is closed, the hinged edge thereof is swung toward and in opposed relation to the door jamb, which causes the actuator to move forward against the counteracting efforts of spring 39, and by reason of the actuator member 29 being entered in the slot 30 in the weather strip, the latter is caused to move forward and downward, thereby closing the space between the lower edge of the door and the floor. During this action the actuator member 29 slides outwardly in slot 30 and in contact with the lower wall of said slot, while when the actuator moves rearwardly, member 29 thereof slides inwardly in said slot and in contact with the upper wall thereof.

If it is found that the door cannot easily close for the reason that the weather strip has too soon come in contact with the floor, the actuator rod 32 may be adjusted in its yoke or frame to diminish the length of projection beyond the hinged edge of the door, and if, when the door is shut, it is found that the space between the lower edge of the door and the floor is not fully closed, said actuator rod may be adjusted to increase the extent of projection necessary. In this manner, the weather strip is adjusted for wear and also for different sizes of spaces between doors and floors. In order to effect an adjustment of the actuator rod it is only necessary to revolve the same to the right or left within the actuator yoke or frame, as may be required.

I have herein resorted to the use of the expressions "rearwardly" and "forwardly" and the like as a convenient manner of expressing direction relative to the hinged and unhinged vertical edges of the door, it being my intention to consider the unhinged vertical edge of door the forward edge and the hinged edge of the rear edge.

Having thus described my invention, what I claim is,—

1. In a weather strip for the bottoms of doors, the combination with a door having a longitudinal groove in its lower edge, of a longitudinal strip guided in said groove for combined forward and downward and for opposite movements, said longitudinal strip having a rearwardly and downwardly directed slot in its upper edge adjacent its rear end, an actuator comprising a yoke having a downwardly and rearwardly inclined actuator member entering said slot, a rod threaded into opposite ends of said yoke for adjustment therein and having its rear end projecting from the rear or hinged edge of the door for engagement with a door jamb, and its front end guided for movement and a spring acting against said actuator to hold said rod projected and said longitudinal strip raised when the door is open, said longitudinal strip being lowered to extend from the groove of said door and said rod being 120

forced forwardly against the action of said spring when the door is closed.

2. In a weather strip for closing the bottoms of doors, the combination of a door having a longitudinal groove in its lower edge enlarged in depth at its rear end to provide a shoulder, a plate secured to the rear or hinged edge of said door, a longitudinal strip guided in said groove for combined forward and downward movement and for reverse movement, said strip having a downwardly and rearwardly directed slot in its upper edge near its rear end, an actuator in the enlarged part of said groove 10 consisting of a yoke and a rod passing through said yoke, said yoke comprising a longitudinal member, depending arms at opposite ends of said longitudinal member and

a rearwardly and downwardly inclined actuator member entered in the slot of said longitudinal strip, said rod having opposite ends guided for movement, respectively, in a bore extending forwardly from said shoulder and in the plate secured to the rear or hinged edge of said door, said rod projecting rearwardly beyond said plate for contact with a door jamb, and a spring surrounding said rod and bearing at one end against said shoulder and at its other end against said yoke. 20 25 30

In testimony whereof I affix my signature in presence of two witnesses.

HENRY BAUER.
